UNITED STATES PATENT OFFICE

151,402

DESIGN FOR A TIE-RACK

Thomas J. Ragland, Seattle, Wash.

Application May 17, 1946, Serial No. 129,772

Term of patent 7 years

(Cl. D33—8)

To all whom it may concern:

Be it known that I, Thomas J. Ragland, a citizen of the United States and a resident of Seattle, in the county of King and State of Washington, have invented a new, original, and ornamental Design for a Tie-Rack, of which the following is a specification, reference being had to the accompanying drawings, forming a part thereof.

In said drawings:

Figure 1 is a top plan view of a tie-rack, showing my new design.

Fig. 2 is a side elevational view thereof; and Fig. 3 is a front elevational view thereof.

The characterizing feature of my design for the tie-rack shown resides in the specific configuration of the supporting bracket.

I claim:

The ornamental design for a tie-rack, as shown and described.

THOMAS J. RAGLAND.
